(57) **CLAIM**

The ornamental design for a spacecraft, as shown and described.

DESCRIPTION

FIG. 1 is a front elevation view of a spacecraft showing our new design and where the rear and side views are mirror images of FIG. 1 and therefore not shown;

FIG. 2 is a top plan view thereof;

FIG. 3 is a top perspective view thereof;

FIG. 4 is a bottom plan view thereof;

FIG. 5 is a bottom perspective view thereof; and, FIG. 6 is a bottom perspective view thereof shown in an environment of use.

1 Claim, 3 Drawing Sheets

FIG. 1

FIG. 2

FIG. 3

FIG. 4

FIG. 5

FIG. 6
